ELECTRIC SWITCH

Arthur C. Gaynor, Stratford, Conn.

Application October 30, 1929, Serial No. 403,437
Renewed May 31, 1934

14 Claims. (Cl. 200—67)

This invention relates to electric switches, and more particularly, to the snap or quick acting types.

An object of the present invention is to provide a switch which may be made relatively small but in which the parts are of substantial size so that relatively heavy currents may pass through the switch.

Another object of the present invention is to provide an enclosed toggle switch of such small dimensions that it may be conveniently mounted in a handle of a vacuum cleaner or other electrical appliance.

Another object is to provide a switch in which the contacts are so arranged that the wire ends may be secured thereto while the contact ends are out of the switch, the contacts being securely held in place by the switch body when the switch is assembled.

Other objects and advantages will hereinafter appear.

In the accompanying drawing which shows one form of the invention, that at present preferred—

Figure 1 is a sectional view of the switch taken on the line 1—1 of Fig. 2.

Fig. 2 is a top plan view of the switch.

Fig. 3 is a side elevation of the switch.

Fig. 4 is a bottom plan view, showing a portion of the body of the switch broken away to expose the operating parts within the switch.

Fig. 5 is a transverse sectional view taken on the line 5—5 of Fig. 1.

Fig. 6 is an end elevation of the switch.

Fig. 7 is a fragmentary view showing the switch mechanism in "on" position.

Fig. 8 is a disassembled end view of the switch mechanism.

Fig. 9 is a similar view of a modified form of the mechanism shown in Fig. 8.

As shown in the accompanying drawing, the switch of the present invention comprises an insulating body 10 divided longitudinally into two parts or insulating blocks 11, which are semi-circular in form and fit together as shown in Figs. 2 and 4. The meeting faces of the blocks 11 are recessed to provide a chamber 12 in which the switch mechanism is located, and this recess extends to the exterior of the body 50 where it forms a longitudinal slot 13 extending from close to one end of the body to close to the other end and through which a bar-like handle 14 extends for manual engagement to actuate the switch mechanism. The handle 14 55 fills the slot 13 leaving only sufficient clearance

between itself and the walls of the slot for free oscillation.

The body is adapted to be supported by a yoke 15 having screw-receiving holes 16 by means of which the switch may be mounted on a supporting structure and having depending ears 17 adapted to embrace the sides of the body 10. In the form of the invention shown herein, the yoke has two depending ears 17, one at each side of the body and lying in recesses 18 65 on the sides of the body.

The two insulating blocks 11 constituting the body may be secured together and then be secured to the ears 17 of the supporting yoke. However, according to this invention, the insulating blocks 11 are held together and are secured to the supporting yoke ears 17 by the same means, thus effecting a saving in the number of parts required for the switch.

Accordingly, each block 11 is provided with a 75 screw-receiving metal insert 19 aligned with a hole 20 in the other block 11, through which the insert projects. The holes 20 and inserts 19 are adapted to align with similar holes 21 in the yoke ears 17 so that after the two blocks 11 are 80 fitted together, the yoke ears may be slid down through the recesses 18 until the holes 21 in the yoke ears align with the holes 20, whereupon headed screws 22 may be inserted and adjusted in the inserts 19 in the opposite blocks 11. By 85 this simple means, the blocks are held together and the yoke is secured to the blocks.

The yoke 15 is provided with an elongated aperture 23 through which the handle 14 may be operated. In order that the handle need 90 not have sliding contact with the walls of the aperture in the yoke and yet to provide a flush surface at the top of the switch, the perimeter of the straight edge of the body is provided with a shoulder 24 adapted to fit within the aperture 95 23 of the yoke, permitting the surface 25 of the yoke to be flush with the surface 26 of the body.

Preferably, the aperture 23 in the yoke is made to snugly fit over the shouldered portion 24 of the body to firmly embrace the blocks 11 constituting the body and prevent any tendency of the blocks to spread apart at the straight edge through which the operating handle 14 extends.

The switch mechanism of the present invention is of the toggle type and comprises a contact-bridging member 27 in the form of a roller having an axle 28 carried by links 29 mounted on an axle 30 to swing from one position of rest where the roller engages abutments 31 on the body (see Fig. 1) to another position of rest 110

where the roller engages a pair of contacts 32 to close a circuit including said contacts. The links 29 are so designed that the contact-bridging roller 27 does not engage the adjacent surfaces 33 of the body but swings clear of it.

The switch mechanism also includes an arm 34 whose lower end has a socket 35 engaging the contact-bridging roller's axle 28 and carrying at its upper end a slidable head 36 adapted to be engaged by an operating arm 37 carried by the handle 14 which, it should be noted, is fulcrumed on the axle 30 which also carries the links 29. Interposed between the sliding head 36 and shoulders 38 on the arm 34 is a coil spring 39 which tends to hold the switch mechanism and the operating handle 14 in either of two positions of rest, the spring urging the operating arm 37 upwardly and causing the lower edge 40 on the handle to engage a stop 41 on the body.

When the handle is rocked, the operating arm 37 thereon presses the sliding head 36 downwardly compressing the spring 39. While doing so, due to a knife edge 42 on the operating arm 37 engaging a depression 43 in the sliding head 36, the arm 34 is rocked about its mounting on the roller axle 28, and thus the upper end of the spring is carried beyond a line drawn through the axle 30 for the handle and the axle 28 for the contact-bridging roller 27. When this occurs, the spring may again expand and in doing so moves the end of the arm 34 engaging the roller 27 away from the stop 31 toward the contacts 32, or vice versa, according to the previous condition of the switch, and at the same time completes the rocking movement of the handle until one of the stops 41 is engaged by one of the ends 40 of the handle. During this movement, the roller 27 is guided solely by the links 29.

In moving from the position shown in Fig. 1 to the position shown in Fig. 7, the roller strikes inclined surfaces 44 of the contacts 42 and rises until it strikes vertical surfaces 45 of the contacts. This is permitted by providing looseness as by a slot 47 between the links 29 of their axle 30, and as a result of this movement, the spring 39 may act to resiliently press the roller into the depression formed by the sloping surfaces 44 and the vertical surfaces 45 of the contacts, and thus insures good electrical engagement between the bridging-roller 27 and the contacts.

In the illustrated embodiment of this invention, the handle 14 shown is formed like the handle in the patent to Kloss #1,510,064, and comprises a bar having two contiguous surfaces 46 angularly disposed with relation to each other for manual engagement to operate the switch. The angle between the surfaces 46 is such that in each position of rest of the switch one of the surfaces 46 is substantially parallel with the straight edge of the body and the supporting yoke, the other surface 46 sloping upwardly from a medium point and being always the next surface to be operated to change the condition of the switch.

As shown herein, the operating arm 36 for the handle may be a metal piece inserted in the handle during the molding thereof, but the handle itself is made of insulating material so that a person operating it will not receive an electrical shock in doing so, for it should be noted that the other moving parts of the switch are metallic and are in electrical engagement with the contact-bridging roller 27.

The axle 30 for the handle is mounted directly in the blocks 11, and thus the provision of a separate supporting frame in the body for the axle is avoided. The bearing for the axle 30 is constituted by sockets 48 in the blocks in which the axle fits. These sockets are closed at the outside of the blocks so that no electrical contact may be made thereto. Moreover, by providing the sockets 48 instead of holes, end thrust on the axle is absorbed by the body and consequently the axle need not be fastened to the handle or other parts but may be merely a pin having a sliding fit therewith.

The recesses 12 and the meeting faces 11 of the blocks 11 also open to the exterior at the curved edge of the body and there provide a slot 49 in which the contacts 32 may be located so that ears 50 on the contacts may be located at the exterior of the body where they are provided with wire-attaching screws 51. The contacts 32, which are formed of flat pieces, are adapted to be mounted on the blocks 11 and secured firmly in place without the use of tools and so that when the blocks 11 are secured together the contacts 32 cannot be moved or removed. To accomplish this, each of the contacts 32 is provided with an aperture 52 adapted to fit over and be supported by a similarly shaped lug 53 on one of the blocks 11 when the blocks are apart, and the apertures 52 and lugs 53 are non-cylindrical so as to prevent turning movement of the contact when supported on the lug. When the blocks 11 are assembled, the contacts lie parallel with each other and with the walls of the body.

The contacts are insulated from each other and held in position against sidewise motion by a block 54 of insulating material which has an aperture 55 adapted to align with the apertures 52 in the contacts and to fit over both lugs 53 when the blocks 11 of the body are brought together. In assembling the switch, a contact 32 is placed on each lug 53 and then the insulating block 54 is placed on one of the lugs, and finally when the two parts 11 are put together, the lug on the other block is pressed into the aperture 55 in the insulating block 54. The insulating block 54 simultaneously engages both blocks 11 of the body and thereby aligns the blocks relative to each other, and also prevents endwise and turning movements of one block relative to the other even before the screws 22a are tightened in place.

The insulating block 54 and contacts 32 completely fill the slot 49 in the body through which they extend, and their outside surfaces for the most part conform to the contour of the body. The insulating block 54 extends out beyond the body and is located between the ears 50 of the contacts so as to electrically isolate the ears and has holes 56 through which the wire-attaching screws 51 extend for protecting the screws against contact with extraneous bodies.

As shown in Figs. 1 and 7, the inclined surfaces 44 and the vertical surfaces 45 of the contacts project beyond the adjacent surfaces of the insulating body 54, so that the roller 27 will engage these surfaces of the contacts and not be held from engagement therewith by the insulating block.

The arm 39 may be made, as shown in Fig. 8, of two flat pieces 39a, the lower ends of which are spaced by a disk 57 on the roller axle 28, while the upper ends project through slots 58 in the sliding head 36 where they are provided

with enlargements 59 for preventing the sliding head 36 from inadvertently slipping off, the enlargements 59 also embracing the end of the operating arm 37, and preventing sidewise movement of the arm 39 at that point. If desired, the arm 39 may be formed of one piece 39b bent in U-shape form as shown in Fig. 9, in which arrangement the cross-bar 60 of the U-shaped piece acts to space the lower ends 10 of the legs 61 thereof, and consequently the disk 56, used in the form shown in Fig. 8, is not needed.

Frequently, it is desired to have the switch normally biased to the one position, say "off" position, so that it is necessary to manually hold the switch in "on" position. This is accomplished in the form of the invention herein shown by providing the handle 14 with depressions or sockets 62 for receiving one end of a returning spring 63, the other end of which may rest on the top of the insulating block 54, as shown in Fig. 1, or on the stop 41 if the spring is placed in the other side of the handle. With this simple arrangement, to convert the switch from one which may be left in either position of rest to one which is normally biased to one position, it is merely necessary to insert the spring 63 in the desired socket 62 when the switch is assembled, and should it at any time be desired to reconvert the switch, it is merely necessary to remove the screws 22, separate the parts 11, and remove the spring 62 or place it in the other socket.

By having the contacts mountable and demountable from the parts 11 without the use of tools, the assembly of electrical devices with the switches is materially facilitated, for the wire ends may be secured under the screws 51 before the contacts are assembled in the switch, it being merely necessary then to place the contacts over the lugs 53 when assembling the switch.

Variations and modifications may be made within the scope of this invention and portions of the improvements may be used without others.

Having thus described the invention, what is claimed as new and for which it is desired to obtain Letters-Patent, is:—

1. In an electric switch, an insulating body comprising two insulating blocks having their meeting faces extending longitudinally of the body, said meeting faces being recessed to form a chamber open at one edge of the body; switch mechanism in the recess in said body including a handle extending through said recess to the exterior of the body for manual operation, said recessed edge of the body having a shoulder around its perimeter; and a supporting yoke having an aperture through which the recessed edge of the switch passes and against the walls of which the shoulder on the body snugly engages, said yoke being adapted to resist the spreading of the blocks at the recessed edge of the body through which said handle passes.

2. In an electric switch, an insulating body comprising two insulating blocks having their meeting faces extending longitudinally of the body, said meeting faces being recessed to form a chamber open at one edge of the body; switch mechanism in the recess in said body including a handle extending through said recess to the exterior of the body for manual operation, said recessed edge of the body having a shoulder around its perimeter; and a supporting yoke having an aperture through which said recessed

edge of the switch passes, said yoke embracing said recessed edge of the body and being adapted to resist the spreading of the blocks at the recessed edge through which said handle passes.

3. In an electric switch, an insulating body comprising two semi-circular blocks having their meeting faces extending longitudinally of the body, said meeting faces being recessed to form a switch chamber open at the straight edge of the body; switch mechanism in the chamber; and means for actuating said switch mechanism including a handle extending through and completely filling the opening of the recess at the straight edge of the body, said handle having an elongated bar reaching substantially from end to end of the body and being mounted to teeter from one position of rest to another to operate the switch mechanism.

4. In an electric switch, an insulating body comprising two insulating blocks having their meeting faces extending longitudinally of the body, said meeting faces being recessed to form a switch chamber and said recess including a slot opening at one edge of the body; a switch mechanism in said chamber including a contact-bridging member; two parallel contacts located in said slot in the body extending into said recess for engagement with said contact-bridging member and extending to the exterior of the body for wire engagement, said contacts being provided with elongated apertures; and a lug on each of said blocks adapted to engage with the aperture of one of the contacts to support the latter on the block against turning movement.

5. In an electric switch, an insulating body comprising two insulating blocks having their meeting faces extending longitudinally of the body, said meeting faces being recessed to form a switch chamber and said recess including a slot opening at one edge of the body; a switch mechanism in said chamber including a contact-bridging member; two parallel contacts located in said slot in the body extending into said recess for engagement with said contact-bridging member and extending to the exterior of the body for wire engagement, said contacts being provided with elongated apertures; a lug on each of said blocks adapted to engage with the aperture of one of the contacts to support the latter on the block against turning movement; and insulating means between said contacts and with the contacts completely filling said slot, said insulating means being apertured to receive the lugs on the blocks whereby the insulating means is supported on the bodies against turning movements.

6. In an electric switch, an insulating body comprising two insulating blocks having their meeting faces extending longitudinally of the body, said meeting faces being recessed to form a switch chamber and said recess including a slot opening at one edge of the body; a switch mechanism in said chamber including a contact-bridging member; two parallel contacts located in said slot in the body extending into said recess for engagement with said contact-bridging member and extending to the exterior of the body for wire engagement, said contacts being provided with elongated apertures; a lug on each of said blocks adapted to engage with the aperture of one of the contacts to support the latter on the block against turning movement; and insulating means between said contacts and with the contacts completely filling said

- slot, said insulating means being apertured to receive the lugs on the blocks whereby the insulating means is supported on the bodies against turning movements, said insulating means being adapted to hold the two blocks in alignment before the blocks are secured together. 80
7. In a sandwich type switch having a body split longitudinally and formed of two insulating blocks, switch mechanism in the body including a contact-bridging member; a lug formed integral with each of the two blocks of the body; a contact mounted on each of said lugs for quick removal and held against removal when the two parts of the body are placed together; and means for securing the two parts of the body together. 85
8. In an electric switch, an insulating body comprising two insulating blocks having their meeting faces extending longitudinally of the body; means for securing the blocks together in alignment; a third insulating block interposed between said first-named blocks; and integral interengaging means in said third block and first-named blocks for aligning the latter preparatory to the securing of the first-named blocks together by the securing means. 90
9. In a snap switch, a circuit closing member; a spring for causing the circuit-closing member to move with a snap action from one position of rest to another; a bar-like pivoted handle for operating the switch; a spring for biasing the handle so that it normally moves to one position and must be held manually in the other position; sockets in said handle at opposite sides of its pivot into either of which the spring may be placed to change its biasing action; and abutments adjacent the sockets for the spring. 95
10. In a snap switch, a circuit closing member; a spring for causing the circuit-closing member to move with a snap action from one position of rest to another; a bar-like pivoted handle for operating the switch; a spring for biasing the handle so that it normally moves to one position and must be held manually in the other position; a socket in said handle at one side of its pivot into which the spring may be placed; and an abutment adjacent the socket for the spring. 100
11. In a snap switch having a base; a circuit closing member; a spring for causing the latter to move with a snap action; a bar-like handle pivotally mounted on said base; abutments on the base under the handle for limiting its move- 105
- ments; and means inserted between one side of the bar-like handle and one of said abutments for biasing the handle so that it normally moves to one position and must be manually held in one position. 110
12. In an electric switch, operating mechanism comprising a pair of rocking members, one of said members comprising a handle with a knife-edge operating portion and the other comprising a roller; a pair of straps bearing on the roller axle; a spring surrounding said straps; shoulders at one end of said straps for engaging one end of the spring; a member slidably mounted on said straps and engaging the other end of said spring and having a depression in which the knife-edge of the operating member engages; and a disk on the roller holding the lower ends of said straps spaced apart. 115
13. In an electric switch, an insulating body comprising two insulating blocks having their meeting faces extending longitudinally of the body, said meeting faces being recessed to form a chamber open at one edge of the body; switch mechanism in the recess in said body including a handle extending through said recess to the exterior of the body for manual operation, said recessed edge of the body having a shoulder around its perimeter; and a supporting member having an aperture through which the recessed edge of the switch passes and against the walls of which the shoulder on the body snugly engages, said supporting member being adapted to resist the spreading of the blocks at the recessed edge of the body through which said handle passes. 120
14. In an electric switch, an insulating body comprising two insulating blocks having their meeting faces extending longitudinally of the body, said meeting faces being recessed to form a switch chamber and said recess including a slot opening at one edge of the body; a switch mechanism in said chamber including a contact-bridging member; two parallel contacts located in said slot in the body extending into said recess for engagement with said contact-bridging member and extending to the exterior of the body for wire engagement, said contacts being provided with non-circular cutouts; and a lug on each of said blocks adapted to fit the cutout of one of the contacts to support the latter on the block against turning movement. 125
